UNITED STATES PATENT OFFICE.

GEORGE ELIAS, OF IRVINGTON, AND WILLIAM MENDEL, OF NEWARK, NEW JERSEY.

ELECTRIC-LIGHT SHADE.

1,217,582.

Specification of Letters Patent. Patented Feb. 27, 1917.

Application filed April 3, 1916. Serial No. 88,441.

To all whom it may concern:

Be it known that we, GEORGE ELIAS and WILLIAM MENDEL, both citizens of the United States, and residents of Irvington 5 and Newark, respectively, in the county of Essex and State of New Jersey, have invented certain Improvements in Electric-Light Shades, of which the following is a specification.

10 This invention relates to translucent shades of porcelain or the like which are employed with high power incandescent lamps, such as nitrogen lamps, to secure a system of semi-indirect lighting, the lower 15 part of the bulb being inclosed in a globe shade open at its top and having a disk-like reflector arranged a little distance thereabove around the neck of the bulb.

The objects of the invention are to provide improved supporting means for the globe part of the shade; to enable the reflector to be fluted or otherwise ornamenteally shaped to diffuse the light; to support the globe with least possible obstruction to 25 light; to support said globe so that it will not fall even if the edge of the reflector chips off; to support the globe from the middle of the reflector where it is supported; to employ flexible members to carry the 30 globe; to thus permit the globes and reflectors to be of different relative sizes; to hold the flexible members spaced in proper angular relation to each other; to secure simplicity of construction and at the same 35 time a pleasing and artistic effect, and to obtain other advantages and results as may be brought out in the following description.

Referring to the accompanying drawings, in which like numerals of reference indicate 40 the same parts throughout the several views,

Figure 1 is a plan view of a light shade embodying our invention;

Fig. 2 is an elevation of the same, and

Fig. 3 is a detail view of a clip which can 45 be employed on the globe.

In the specific embodiment of the invention illustrated in said drawings, the reference numeral 1 indicates an electric light socket of any suitable or well-known type 50 having thereon the usual shade holder 2 and carrying a lamp or bulb 3. Supported by the shade holder in the usual manner is a reflector 4, which may be of glass, porcelain or any other material adapted to the 55 purpose. It is to be noted that this reflector provides at its middle part a neck

5 from which the body portion flares outwardly and downwardly, said neck being adapted to enter the holder 2 and having an enlarged or flare top 6 beneath which the 60 screws 7 of the holder project, as is usual. The body portion 8 of the reflector is preferably annular and furthermore is preferably fluted or undulatory, providing a series of wave-like ridges 9 extending radially of 65 the reflector. These ridges are of greatest height at the periphery of the reflector and diminish in height toward the center, preferably disappearing entirely before reaching the neck 5. It will be understood that 70 this is the preferred form of the body portion of our reflector, although it is within the scope of our invention to have it plain cone-shaped or of any suitable form.

Around the neck 5 of the reflector is a 75 ring 10 of any suitable construction and material, and at separated points around this ring, preferably at even distances apart, connecting members 11, preferably flexible such as chains, are attached thereto. These 80 connecting members 11 extend radially of the reflector 4 and lie each in a hollow or groove 12 between two ridges 9 of the reflector, so that they are held by said ridges in proper spaced relation around the reflector, especially at its periphery. The 85 members 11 bend over the edge or periphery of the reflector, extending below the same, and are connected at their ends to clips 13 upon the globe 14. It will be noted that 90 this globe is open at its top, and that the lamp or bulb 3 depends into the same from the socket 1. The globe may be frosted or otherwise made to diffuse the light shining therethrough, and a little space is left between the globe and the reflector to obtain 95 an indirect illumination by reflection.

The clips 13 may be of any kind adapted to suitably engage the beaded rim 15 of the globe and receive the connecting members 100 11. For purposes of illustration, we have shown spring clips which snap onto the rim and frictionally engage it, providing eyes 16 at their upper ends to detachably receive hooks 17 on the ends of the connecting 105 members 11. Said connecting members being preferably flexible, or chains, as stated, the globe can adjust itself with respect to the reflector and hang freely and naturally. The entire shade will thus assume a symmetrical appearance automatically, the fluted reflector keeping the connecting mem- 110

bers 11 in proper relative position. The ring or band 10 upon the reflector, to which the connecting members are attached, is preferably cut out of sheet metal and split 5 or divided in any suitable manner to pass over the neck 5 of the reflector and lie flat upon the body portion 8 of the reflector, as shown. For illustration, we have shown one end of the ring slotted as at 18 to receive a 10 tongue 19 on the other end, but any other suitable construction might be employed.

By our improved construction there are no screws or other loose and removable parts to become lost or broken, and the weight 15 of the globe is carried by the ring at the center of the reflector, so that in case the reflector becomes chipped or broken at its edge, the globe is still supported and not allowed to fall. Also, the clips and chains 20 are not conspicuous, adding to rather than detracting from the pleasing appearance of the light shade, and interfering the least possible amount with the radiation and reflection of the light. Furthermore, the reflector, by use of the chains, may be much 25 larger than the diameter of the upwardly open rim of the globe, obtaining greater efficiency in reflection and adapting the light to meet varying conditions and tastes, 30 in that a large or small globe may be used with a reflector and vice versa.

Obviously many detail modifications and changes may be made in the manufacture of our improved electric light shade without 35 departing from the spirit and scope of the invention, and we do not wish to be understood as limiting ourselves except as required by the following claims when construed in the light of the prior art.

40 Having thus described the invention, what we claim is:—

1. An electric light shade comprising in combination a reflector with a neck adapted to receive a lamp socket and be attached thereto, a globe below said reflector, and means extending from adjacent said neck radially of the reflector above the same beyond its edge to the globe for supporting said globe.

50 2. An electric light shade comprising in combination a reflector with a neck adapted to receive a lamp socket and be attached thereto, a globe below said reflector, a ring or band around the neck of the reflector, and connecting means extending from said ring

over the edge of the reflector for supporting said globe.

3. An electric light shade comprising in combination a reflector with a neck adapted to receive a lamp socket and be attached thereto, a ring or band around said neck, connecting members extending from said band radially of the reflector beyond its periphery, and a globe supported by said connecting members beneath the reflector. 60

4. An electric light shade comprising in combination a reflector with a neck adapted to receive a lamp socket and be attached thereto, a ring or band around said neck, flexible connecting members extending from 70 said band radially of the reflector beyond its periphery, and a globe supported by said connecting members beneath the reflector.

5. An electric light shade comprising in combination a reflector with a neck adapted to receive a lamp socket and be attached thereto, a globe below said reflector, and means extending from adjacent said neck radially of the reflector and supporting said globe, said means being positioned circumferentially of the reflector by peripheral recesses therein. 75

6. An electric light shade comprising in combination a radially fluted reflector, a globe below said reflector, and means retained in position by the flutings of the reflector for suspending the globe from the reflector. 85

7. An electric light shade comprising in combination a fluted reflector providing an 90 annular series of radially extending ridges and hollows, a globe below said reflector, flexible members lying in said hollows of the reflector and held thereby in spaced relation for supporting said globe, and means 95 extending around the middle part of said reflector for supporting said members.

8. An electric light shade comprising in combination a fluted reflector providing an annular series of radially extending ridges 100 and hollows and having at its middle an upwardly extending neck, a globe below said reflector, a ring extending around said neck, and chains carried by said ring and lying in the hollows of said reflector and held thereby in spaced relation for supporting said globe. 105

GEORGE ELIAS.
WILLIAM MENDEL.
